UNITED STATES PATENT OFFICE.

LEMUEL COBURN AND WILLIAM J. SUMNER, OF HOLYOKE, MASSACHUSETTS,
ASSIGNORS TO THE COBURN TROLLEY TRACK MANUFACTURING COMPANY, OF SAME PLACE.

DOOR-HANGER.

SPECIFICATION forming part of Letters Patent No. 460,501, dated September 29, 1891.

Application filed March 2, 1891. Serial No. 383,507. (No model.)

To all whom it may concern:

Be it known that we, LEMUEL COBURN and WILLIAM J. SUMNER, citizens of the United States, residing at Holyoke, in the county of 5 Hampden and State of Massachusetts, have invented new and useful Improvements in Hangers for Doors and other Movable Parts, of which the following is a specification.

This invention relates to improvements in 10 rolling supports, which are movable on suitable tracks, for doors, ladders, fire-escapes, or other bodies, apparatuses, or loads, the object of such invention being the provision of a carrier for the purpose indicated which is 15 of unusual efficiency, whereby the weight of the article or thing to be supported shall be most evenly distributed upon the wheels or rollers embodied in the contrivance, so that the wear of the parts shall not be marked or 20 excessive in any one part of the device.

Another object of the invention consists in the capability which the rolling carrier or support possesses for always remaining lubricated and free-running.

25 The invention consists in the construction and combination of parts, all substantially as will hereinafter more fully appear, and be set forth in the claims.

In the accompanying drawings, forming 30 part of this specification, the present improvements are illustrated.

Figure 1 is a view in perspective showing a portion of a trolley-track, the roller-carrier, and the upper part of a door shown as supported on and pending therefrom. Fig. 2 is 35 a perspective view of the part of the carrier which is directly supported on the rollers. Fig. 3 is a cross-section of the track and carrier on the line 3 3, Fig. 1.

40 The trolley-track A has parallel ways *a a*, upon which the pintle-united rollers *b b* run. The said pintle-united rollers and the part B, sustained thereon, constitute the roller-carrier, and the said roller-supported part B, which 45 is essential to this invention will be now particularly described. The said carrier-body B has a pair of thin, though rigid, side bars *d d* of metal, and in practice a desirable length therefor for the most ordinary use of 50 the device is about five inches, and said bars

are ranged side by side in parallelism longitudinally of the track and clamp between their end portions comparatively short blocks *ff* of suitable material, wood being preferred. These wood blocks have within their under 55 edges between their ends transverse semi-circular recesses *g*, which extend from side to side of the block. The portions of the thin metal side bars which are adjacent the transverse block-recesses are themselves recessed, 60 as shown at *h*, while the said blocks as ordinarily formed have the widened portions which fit and fill out the recesses in the side strips, making for the carrier-body B even and smooth sides. The blocks and strips are 65 firmly and compactly united by the transverse rivets *j*, and there is, of course, within the side strips and between the inner ends of the blocks an opening *k*, across which passes the pin or bolt *m*, which is removably supported by resting within the holes *n* formed through the strips *d*. The pin *m* on being 70 removed permits of the passage within the middle aperture *k* of the carrier-body of a hanger or lug, one of such being shown at *o*, 75 the pin on being returned engaging said hanger or lug.

The wood blocks are to be saturated and thoroughly permeated with melted tallow, oil, or any fatty material, and by this means 80 the permanent lubrication at the bearing between the carrier-body and the axle or roller-pintles is assured—an advantage which is of importance, especially in a roller-carrier which runs within a tubular double-way track such 85 as shown in the drawings, and which track itself is often inclosed or otherwise inaccessible.

The weight of the carrier-body and of the door or load sustained thereon is borne 90 through the contact of the roller-pintles with the wood blocks at the recessed portions *g* of the latter, and as the wear takes place it is entirely, so far as the carrier-body is concerned, evenly of and upon the said blocks. 95 The nature of the fat-saturated blocks is such that while the wear is slow and smooth, and as the parts are used they move noiselessly, the portions as they are worn away at the bearings only bring to the contact of the 100

roller-pintles such new wood surfaces as are equally efficient for lubrication, smooth wear, and noiseless bearing.

What we claim as our invention is—

- 5 1. A roller-carrier for the purpose substantially as set forth, consisting of opposing pairs of metallic strips provided intermediately thereof at their end portions with wood blocks, the said strips and blocks being firmly con-
10 fined together, leaving the intermediate space within the strips and between the inner ends of the blocks, bearings formed in the under sides of the blocks, and a supporting member, as the pin *m*, supported on said strips, and
15 rollers having uniting axles, on which said blocks directly bear, substantially as de-
scribed.
2. The combination, with a tubular trolley-
track having at its under side double parallel

ways with an intermediate slot, substantially 20 as described, and two pairs of double and pintle-united rollers adapted to run in said track, of a carrier-body consisting of parallel and opposing longitudinally-ranging metallic side strips, and blocks of wood *ff*, rigidly 25 confined between the end portions of said side strips, leaving the intermediate space, as *k*, the cross member traversing said space and supported on said strips, and a hanger adapted for engagement with said support- 30 ing member and to extend downwardly, to be connected with the part to be carried, sub-stantially as set forth.

LEMUUEL COBURN,
WILLIAM J. SUMNER.
